UNITED STATES PATENT OFFICE.

ARTHUR B. MODINE, OF RACINE, WISCONSIN.

AUXILIARY TANK AND MEANS FOR MAINTAINING THE TEMPERATURE OF A CIRCULATING FLUID.

1,233,100.

Specification of Letters Patent. Patented July 10, 1917.

Application filed July 17, 1915. Serial No. 40,437.

To all whom it may concern:

Be it known that I, ARTHUR B. MODINE, a citizen of the United States, residing at Racine, in the county of Racine and State 5 of Wisconsin, have invented certain new and useful Improvements in an Auxiliary Tank and Means for Maintaining the Temperature of a Circulating Fluid, of which the following is a description.

10 My invention relates to the cooling system for any mechanism where there is liability of annoyance from great changes of temperature of the circulating fluid when the mechanism is not in operation, such for 15 example, as the internal combustion motors used on automobiles or other devices.

The object of my invention is to provide 20 a simple, reliable, inexpensive and convenient device of the kind described wherein the circulating fluid is removed from the system when the mechanism is not in service 25 and temporarily stored in a thoroughly protected and insulated receptacle with means for returning the fluid to the circulating system as soon as the mechanism is started.

To this end my invention consists in the novel construction, arrangement and combination of parts herein shown and described, and more particularly pointed out 30 in the claims.

In the accompanying drawings wherein like or similar reference characters indicate like or corresponding parts:

Figure 1 is a side elevation of an internal 35 combustion motor and circulating system of an automobile provided with my improvement with parts removed and broken away to more clearly show the construction.

Fig. 2 is a sectional detail view of the 40 valve for controlling the flow of fluid to my device.

Fig. 3 is a slightly modified form of the connection between the circulating system and my storage reservoir.

45 Fig. 4 is a view similar to Fig. 1 showing a slightly modified form of my device.

Fig. 5 is a fragmentary section taken substantially on line 5—5 of Fig. 4.

Fig. 6 is an enlarged view of the exhaust 50 pipe of the motor showing the form and arrangement of the end of the pipe connecting the same to the fluid storage tank.

Fig. 7 is a view similar to Fig. 6 but showing a slightly modified form of pipe 55 end.

In the drawings for the purpose of illus-

tration I have shown my improvement in connection with the internal combustion motor and circulating system of an automobile in which 1 is the motor, of the usual or any 60 preferred construction having an exhaust manifold 2 substantially of the usual or any desired form. A radiator 3 is connected to the motor 1 by a supply pipe 4 and a return pipe 5 for conducting the fluid from the radiator to the water jacket of the motor and returning the same to the radiator, all constructed and arranged substantially in the usual or any preferred manner.

My improvement consists in the receptacle 6, connected by a pipe 7 preferably to the lowest portion of the circulating system so as to form a convenient, direct passage from the radiator to the receptacle adapted to drain all fluid from the radiator and the system to which it is connected into the receptacle. The size of the receptacle 6 is preferably sufficient to receive all of the fluid from the system leaving a slight open space 8 at the top of the receptacle. In the preferred construction the pipe 7 extends into the receptacle 6 substantially to the bottom thereof as at 9 and a tube 10 extends from the manifold 2 to the space 8 in the receptacle adapted to conduct a portion of the 80 burned gases from the manifold 2 to the receptacle. In the preferred construction also a casing 11 is connected to the part 8 of the receptacle and incloses the pipe 7 and extends along the pipe for any desired distance 90 with a valve 12 at the outer end of the casing so that if desired the valve 12 may be opened and permit the hot gases from the manifold 2 to flow by the pipe 10 into the space 8, thence through the casing 11 around 95 the pipe 7 to the outer end of the casing and escape through the valve 12 thus heating the pipe and the contents thereof. The exterior of the receptacle 6 and that portion of the pipe 7 between the outer end of the casing 11 and the radiator 3 are each prefer-

ably provided with an insulating covering 14 and 15 respectively, to prevent as far as practicable the radiation of heat so that fluid in the pipe and receptacle is normally maintained at a substantially uniform temperature. When thus constructed it is obvious that all fluid in the circulating system will normally flow by gravity into the receptacle 6, when however the motor 1 is started 105 a portion of the hot gases in the exhaust manifold are conducted into the space 8 by

the pipe 10 which is of sufficient capacity to permit a slight escape through the valve 12 and yet maintain a sufficient pressure in the receptacle 6 to force the liquid from the receptacle through the pipe 7 into the radiator 3 thus filling the radiator and circulating system and holding the liquid in the system as long as the motor is in operation. Where the pressure in the exhaust manifold is usually low, the velocity of the escaping gases may be utilized to increase the pressure in the receptacle 6 by forming the end of the pipe 10 as shown in Figs. 6 and 7 so that the open end of the pipe 10 is positioned so as to receive a portion of the moving gases and thus increase the pressure in the pipe 10. Under ordinary conditions the valve 12 may be closed thus preventing the hot gases from passing through the casing 1 to heat the pipe 7. Where however, the parts are exposed sufficiently to chill the parts below the freezing point it is desirable to open the valve 12 thus heating the liquid as it passes through the pipe 7 into the system and preventing undue chilling or freezing. Since the liquid is removed from the water jacket of the motor also the parts will arrive at a satisfactory operating temperature much more quickly than where the water jacket is filled with liquid, thus rendering the starting of the motor much easier.

In the preferred form also a check-valve 16 is provided in the pipe 7 below the radiator 3 so that during summer weather or at normal temperatures the valve will automatically prevent the escape of the fluid from the system. As shown a stem 17 extends through the wall of the valve 16 and engages the closure 18 so that when desired the closure may be held at any desired distance from its seat thus permitting the escape of the fluid from the system to the receptacle 6 to be regulated to suit the varying operating conditions. In this form preferably the closure 18 is longitudinally movable upon the stem 17 a sufficient amount to permit the closure 18 to recede sufficiently to permit a full sized opening through the valve and not interfere with the movement of the liquid from the receptacle into the system.

In the form shown in Fig. 3 the casing 11 is omitted and the insulated covering of the pipe 7 extends the entire length of the pipe to protect the fluid in the pipe from sudden changes of temperature.

In the form shown in Fig. 4 the valve 20 below the radiator 3 is a clutch valve of the usual or any preferred form adapted to permit the free escape of liquid from the radiator to the tank 6 but to prevent its movement in the opposite direction.

In this form a pipe 21 preferably connects the valve 20 to a pipe 22 extending into the tank to a point near its bottom, 65 which is also connected by a pipe 24 to the

upper water connection 5 between the motor jacket and the radiator. The remainder of the device is preferably constructed and arranged substantially as herein before described. When thus constructed the liquid in the cooling system flows into tank 6 when the motor is stopped as hereinbefore explained. When the motor is started however the liquid is forced from the tank through the pipes 22 and 24 and flows directly to the cylinder water jackets and thence into the radiator through the lower water connection 4, thus heating the liquid before it enters the radiator and preventing any danger of trouble due to injecting cold water into a very cold radiator.

While my improvement is intended primarily to guard against freezing or extremely low temperatures of the circulating liquid for the cooling system of internal combustion motors, it also serves a very important and useful purpose in warm weather, viz. that of a storage receptacle for liquid so that the motor may be operated for long periods in locations where a supply of the liquid is inaccessible.

Having thus described my invention it is obvious that various immaterial modifications may be made in my device without departing from the spirit of my invention, hence I do not wish to be understood as limiting myself to the exact form or construction shown.

What I claim as new and desire to secure by Letters Patent is:

1. In a device of the kind described having a mechanism, a liquid for controlling the temperature of said mechanism and a system including a radiator for containing and directing said fluid to said mechanism, in combination with a receptacle adapted to receive the liquid from said system, a passage connecting said receptacle to said system and pneumatic means controlled by the operation of said mechanism for expelling the liquid from said receptacle and maintaining the same in said system.

2. In a device of the kind described having a mechanism, a liquid for controlling the temperature of said mechanism and a system including a radiator for containing and directing said fluid to said mechanism, in combination with a receptacle adapted to receive the liquid from said system, a passage connecting said receptacle to said system, means for controlling the flow of liquid through said passage, and means for expelling the liquid from said receptacle and maintaining the same in said system.

3. In a device of the kind described having a mechanism, a liquid for controlling the temperature of said mechanism and a system including a radiator for containing and directing said fluid to said mechanism, in combination with a receptacle adapted to

- receive the liquid from said system, a passage connecting said receptacle to said system, means for controlling the flow of liquid through said passage toward said receptacle
- 5 without affecting its movement in the opposite direction, and pneumatic means controlled by the operation of said mechanism for expelling the liquid from said receptacle and maintaining the same in said system.
- 10 4. In a device of the kind described having a mechanism, a liquid for controlling the temperature of said mechanism and a system including a radiator for containing and directing said fluid to said mechanism, in combination with a receptacle adapted to receive the liquid from said system, a passage connecting said receptacle to said system, means for regulating the temperature of the fluid in said passage, and means for 15 expelling the liquid from said receptacle and maintaining the same in said system.
5. In a device of the kind described having a mechanism, a liquid for controlling the temperature of said mechanism and a system including a radiator for containing and directing said fluid to said mechanism, in combination with a receptacle adapted to receive the liquid from said system, and maintain the same at a uniform temperature, a passage connecting said receptacle to said system, means for controlling the flow of liquid through said passage, and pneumatic means controlled by the operation of said mechanism for expelling the liquid from 20 said receptacle and maintaining the same in said system.
- 35 6. In a device of the kind described having a mechanism, a liquid for controlling the temperature of said mechanism and a system including a radiator for containing and directing said fluid to said mechanism, in combination with a receptacle adapted to receive the liquid from said system, and maintaining the same at a uniform temperature, a passage connecting said receptacle to said system, means for controlling the flow of liquid through said passage toward said receptacle without affecting its movement in the opposite direction, and pneumatic means controlled by the operation of said mechanism for expelling the liquid from 40 said receptacle and maintaining the same in said system.
- 45 7. In a device of the kind described having a mechanism, a liquid for controlling the temperature of said mechanism and a system including a radiator for containing and directing said fluid to said mechanism, in combination with a receptacle adapted to receive the liquid from said system, and maintaining the same at a uniform temperature, a passage connecting said receptacle to said system, means for controlling the flow of liquid through said passage toward said receptacle without affecting its movement in the opposite direction, and pneumatic means controlled by the operation of said mechanism for expelling the liquid from 45 said receptacle and maintaining the same in said system.
- 50 8. In a device of the kind described, having a mechanism, a liquid for controlling the temperature of said mechanism and a system including a radiator for containing and directing said fluid to said mechanism, in combination with a receptacle adapted to receive the liquid from said system, means for controlling the flow of liquid through said passage toward said receptacle without affecting its movement in the opposite direction—means for regulating the temperature of the fluid in said passage, and means for expelling the liquid from 55 said receptacle and maintaining the same in said system.
9. In a device of the kind described having a mechanism, a liquid for controlling the temperature of said mechanism and a system including a radiator for containing and directing said fluid to said mechanism, in combination with a receptacle adapted to receive the liquid from said system, and maintaining the same at a uniform temperature, a passage connecting said receptacle to said system, means for regulating the temperature of the fluid in said passage and means for automatically expelling the 60 liquid from said receptacle and maintaining the same in said system.
10. In a device of the kind described, an internal combustion motor, and a cooling system including a radiator for containing and directing a cooling liquid to said motor to control the temperature of the motor, in combination with a receptacle adapted to receive the liquid from said system and means for employing the exhaust of said 65 motor for expelling the liquid from said receptacle and maintaining the same in said system.
11. In a device of the kind described, an internal combustion motor, and a cooling system including a radiator for containing and directing a cooling liquid to said motor to control the temperature of the motor, in combination with a receptacle adapted to receive the liquid from said system and means for employing the exhaust of said 70 motor for automatically expelling the liquid from said receptacle and maintaining the same in said system.
- In testimony whereof, I have hereunto 75 signed my name in the presence of two subscribing witnesses.
